STOVE

Bertrand E. Kahn, Cincinnati, and William T. Bradbury, Hamilton, Ohio, assignors to The Estate Stove Company, Hamilton, Ohio, a corporation of Ohio

Application August 31, 1931, Serial No. 560,328

6 Claims. (Cl. 126—39)

This invention relates to stoves.

One of the principal objects of the invention is the provision of a stove having a removable interceptor plate positioned beneath the cooking surface of the stove which is of simple construction, is readily removable, is effective as an interceptor, and for directing fuel flow from the burners to provide for burner ignition from a pilot light.

10 Another object of the invention is the provision in a stove of a readily removable interceptor plate for the reflection of heat to the food containers on the cooking surface.

Another object of the invention is to provide 15 an interceptor plate so positioned and in which the interceptor plate also carries passages forming parts of the stove lighter.

Other objects and advantages of the invention 20 will be apparent from the following descriptions, the accompanying drawings and the appended claims.

In the drawings, which disclose a preferred embodiment of the invention—

Fig. 1 is a plan view of a stove construction in 25 accordance with the present invention; certain of the parts being broken away for clearness of illustrations.

Fig. 2 is a sectional view taken on the line 2—2 of Fig. 1.

30 Fig. 3 is a vertical sectional view taken on the line 3—3 of Fig. 1.

Fig. 4 is a plan view of the bottom side of the interceptor plate, and

Fig. 5 is a sectional view taken on the line 35 5—5 of Fig. 4.

The drawings, in which like characters of reference designate like parts throughout the several views thereof, illustrate a cooking stove which comprises generally a stove supporting frame 10 upon which is mounted a cooking top frame member 11. The cooking top frame surrounds and forms an enclosure for a plurality of burners 12 and the food containing vessels rest upon the upper or cooking surface thereof. 40 Fuel is supplied to the various burners from a manifold 14 to which suitable valves 15 are attached; the valves having control handles 16 by which the flow of fuel to the burners 12 may be regulated.

50 In the illustrated embodiment of the invention, the cooking top frame 11 is formed of a single piece of sheet metal, which is depressed at 18 adjacent the inner edge to form a seat for a closure plate 19 which closes the entire cooking top

frame opening and completes the cooking surface of the stove. The cooking top frame member continues downwardly and inwardly from the depression 18 to form a flange 20 which terminates in a down turned lip 21.

The cover or closure plate 19 is shown as a single integrally formed casting for the support of cooking vessels and has openings 22, defined by down turned annular flanges 23, which stand aligned with the burners 12 positioned therebelow. Circular cover plates 24 are provided for the openings 22 and stand supported upon the flanges 23. The tops of the plates 24 are preferably formed level with the surface of the closure plate 19 so that the entire stove top presents a smooth unbroken surface over which cooking vessels may be readily moved.

The solid unbroken top provided by the cover 19 and plates 24 serves to prevent free dissipation 20 of heat from the burners 12. To restrain the heated air and products of combustion from the burners from passing down into the body of the stove a heat deflecting or intercepting plate 26 is positioned within the opening defined by the cooking top frame lip 21; this plate 26 being at 25 substantially the level of the upper surfaces of the burners 12. As shown, the plate 26 extends across substantially the entire opening as defined by the lip 21, and is cut away at the burners 12 as indicated at 27. The plate openings 27 are 30 preferably of smaller size than the openings in the cover plate 19 which is positioned above the interceptor plate. The plate 26 as shown is formed as a single integrally formed casting, and is provided with upturned flanges 28 surrounding 35 the several plate openings. As the openings 27 are of less size than the related closure plate openings, the portions of the upturned flanges 28 which bind the plate openings 27 serve as a means for somewhat retaining on the plate 26 40 any substance which may be spilled on the cover 19 and which then runs over the edge of a plate opening and down into the stove. Also, these upturned flanges 28 may, where they encircle the burners 12, serve as a guard to prevent cross 45 currents from interfering with proper burner operation,—this being particularly true with respect to products of combustion from the front burners.

A normally burning pilot light 30, which is connected to the source of fuel supply, is provided 50 for ignition of the burners 12. Means are associated with the deflector plate 26 to provide passages whereby unburned fuel issuing from a burner 12 may pass to the pilot flame for flashback ignition of the burner. As shown, the fuel 55

flow passages are formed by attachment of a channeled member 32 to the deflector plate, which member may be a cast or stamped spider. This member 32 comprises a central cup shaped portion 33 having an opening 34 provided in the bottom wall, and outwardly extending trough shaped arms 35 which when assembled to the plate 26 terminate adjacent the burners 12 at the cutaway portion 27 of the deflector plate. The ignition member is attached to the plate 26 so that the open sides of the troughs are closed by contact with the plate to thus form fuel flow passages. The ignition member 32, as shown, is held to the underside of the plate 26 by provision of bolts 36 which extend through the plate and arms 35 and position the member 32 so that the central opening 34 stands aligned with the pilot light 30 and the troughs 35 extend toward the burners 12. Also, the member 32 is attached to the plate 26 so that the cup shaped portion 33 and opening 34 stand vertically aligned with an embossed portion 37 on the interceptor plate in which an opening 38 is provided; the opening 38 serving as a vent hole for the pilot flame.

25 The burners 12, deflector plate 26 and the pilot 30 are all carried on common supporting means shown in the form of spaced bars 40. These bars 40 extend from side to side of the stove and are attached to some part of the stove structure such as the flange 20 of the cooking top frame. As shown, the bars 40 have spaced openings 41 for the attachment of the various parts supported thereon. The burners 12 are provided with laterally extended lugs 42 having a flat bottom face 35 from which spaced pins 44 project for entrance within openings 41 of a bar. The deflector plate 26 has downwardly extending lugs 46 which terminate in pins 47 receivable in other of the bar openings 41. The pilot 30 is carried in a plate 40 48 from which ears 49 project and overlie one of the bars 40. The ears 49 have openings to receive bolts 50 which attach to openings 41 of the supporting bar.

45 The pilot light supporting plate 48 may be formed with an upturned flange 52 which is concentrically related to the pilot jet 53. The flange 52 cooperates with the bottom wall of the ignition member central portion 33 so as to provide a secondary air inlet for the pilot burner which is of controlled size. Primary air enters through an opening 54 in the pilot 30.

55 The provision of the single pair of cross bars which serve as supporting means for the various parts of the stove permits accurate alignment of these parts so that they are readily maintained in proper operating relationship. As the holes 41 are pre-formed, and the engaging pins and openings of the various parts all bear a definite relationship to each associated part, it becomes a 60 very simple matter to assemble these stove parts accurately. The deflector plate is further located by provision of outwardly extending lugs 55 which project from the plate sides to engage the cooking top frame flange so that when placing the deflector plate in assembled position these lugs serve as guides for directing the movement of the plate.

70 While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a stove, a plurality of burners, a frame member having an opening within which the burners are positioned, a readily removable interceptor plate positioned as a closure for the frame opening at substantially the level of said burners, said plate having its corners cut away to provide clearance for the burners, plate supporting means, and means on the plate engageable with the supporting means for positioning the plate relative to the frame opening, said positioning means affording upward withdrawal of the plate from the stove.

2. In a stove, a plurality of burners positioned beneath the cooking surface thereof, and a readily removable substantially flat interceptor plate positioned beneath said cooking surface and at substantially the level of said burners, said plate having cut away portions at each corner providing clearance for the burners and an upstanding flange at the perimeter thereof.

3. In a stove, a plurality of burners, a frame member surrounding and forming an enclosure for said burners, a flange on said frame member, means with said frame member comprising a cooking surface, a readily removable interceptor plate positioned beneath the cooking surface at substantially the level of the burners and within the confines of the frame flange, said plate having openings at the burners, spaced bars attached to said frame member, and means on said burners and plate engageable by a vertical interfitting movement with said bars for support of said burners and plate therefrom.

4. In a stove, a plurality of burners, a frame member surrounding and forming an enclosure for said burners, a flange on said frame member, a readily removable interceptor plate positioned at substantially the level of the burners and within the confines of the frame flange, said plate having openings at the burners, spaced bars attached to said frame member, means on said plate engageable with said bars for support of the plate therefrom, and means projecting from said plate for locating the plate from the frame flange.

5. In a stove, a frame member having an opening therein and providing a burner enclosure, a plurality of cooking top burners and a pilot burner within said enclosure, supporting means for the burners comprising a pair of spaced parallel bars of like shape attached to the frame member and extending across the frame opening, a plate providing a closure for the frame opening and having openings therein for each of said burners, and means for removably supporting the plate from the supporting means independently of the burners and with the burners and burner openings in vertical alignment.

6. In a stove, a frame member having an opening therein and providing a burner enclosure, a plurality of cooking top burners and a pilot burner within said enclosure, said burners having attaching means, a plate providing a closure for the frame opening and having openings therein for each of said burners, said plate having attaching means, and supporting means for independently supporting the burners and plate comprising spaced bars attached to the frame and extending across the frame opening, said bars having duplicate symmetrically arranged holes formed therein for reception of the attaching means of the cooking top burner, the pilot burner and the plate.
